UNITED STATES PATENT OFFICE.

EDWIN HEDRICK, OF KENILWORTH, ILLINOIS, ASSIGNOR TO BAUDER IDENTIFICATION COMPANY, OF CHICAGO, ILLINOIS, A CORPORATION OF ILLINOIS.

METHOD OF REGISTERING FINGER-PRINTS.

1,248,111.

Specification of Letters Patent. Patented Nov. 27, 1917.

No Drawing.

Application filed April 19, 1917. Serial No. 163,287.

To all whom it may concern:

Be it known that I, EDWIN HEDRICK, a citizen of the United States, residing at Kenilworth, in the county of Cook and 5 State of Illinois, have invented certain new and useful Improvements in Methods of Registering Finger-Prints, of which the following is a specification.

Prior to my invention the method commonly employed for making records of finger prints is to take up on the ball of the finger, from a previously inked surface, sufficient ink to coat the ridges of the cuticle with a thin film of coloring matter, without 10 permitting the ink to penetrate into the grooves or recesses between the ridges, and then, by applying the finger to paper or other object upon which the finger print record is to be kept, transfer the ink there- 15 to, thus leaving the imprint of the finger. This process is more or less successful, but is open to certain serious objections, among which may be mentioned that it smears the finger with pigment, which is objectionable 20 from esthetic and sanitary considerations, and the finger print is further liable to smear not only at the time of making the same and while the ink is wet, but even thereafter when the print is exposed to moisture. It has also lately been proposed to 25 reproduce the markings of the ball of the finger by pressing the same upon the paper or article upon which the print is to be recorded, and dusting over the invisible print 30 formed by the thin film of natural oil on the finger an impalpable powder, comprising a pigment such as finely divided lamp black which adheres to the oily lines im- 35 printed on the paper by the ridges of the cuticle, thus making the same plainly visible. Considerable difficulty has been experienced 40 in making impressions produced in this way permanent. It has been proposed to cover them with a coating of varnish, shellac or 45 the like by means of a brush, but it has been found that the action of the latter tends to obliterate or smutch the print, and furthermore the coating so formed has a tendency to crumple the paper and render it brittle, 50 both of which effects are decidedly objectionable in the particular uses to which this invention is to be put. A practice which has met with a fair degree of success in this connection is to spray the print with a fixa-

tive solution, but this process is open to the 55 objection that a superfluous quantity of the solution is apt to be projected onto the print which requires to be blotted or otherwise absorbed, in which operation there is always a considerable risk of smearing the 60 print. It is the purpose of my invention to provide a method of fixing the print which obviates all danger of interfering with the sharpness or definition thereof.

In the practice of my process the print is 65 applied to the paper in the method last described, to wit, by making an invisible imprint of the finger in the natural oil, or in case the finger is deficient in oil the lack may be supplied by pressing the finger upon 70 a surface which is provided with a very thin film of an artificial oil. The print is made visible in the manner above described by brushing it over with a very finely divided pigment, thus producing as hereto- 75 fore a distinct sharp reproduction of the lines of the finger tip which, however, without further treatment is liable to smutch. In order to make the record permanent I apply a wash of very dilute fixative to the 80 reverse side of the paper over an area corresponding to that of the print, and the solution penetrates to the front of the paper causing the particles of pigment to adhere firmly thereto, thus rendering the print ab- 85 solutely permanent. I have found a suitable solution for this purpose to consist in a dilute solution of about five per cent. shellac in alcohol or other solvent of shellac. Preferably a very volatile solvent is used in or- 90 der that the paper may dry quickly. By applying the fixative in this manner the print is not exposed to the danger of smearing due to the application of the liquid to the face thereof whether by a brush or spray. 95

I claim:

A process for the production of permanent finger prints upon paper consisting in forming an imprint upon the paper by pressing on the surface of the paper the 100 finger having a thin film of adhesive thereon, dusting a finely divided pigment on the print so formed, and fixing the print by applying to the reverse side thereof a penetrat- 105 ing fixing solution.

In testimony whereof I affix my signature.

EDWIN HEDRICK.
